Des. 228,688
Patented Oct. 16, 1973

228,688

MULTI-STAGE AEROSPACE CRAFT

Hugh L. Dryden, Deputy Administrator of the National Aeronautics and Space Administration, with respect to an invention of Donald Lee Kelly, Sunland, Calif.

Filed Feb. 20, 1964, Ser. No. 78,766

Term of patent 14 years

Int. Cl. D12—07

U.S. Cl. D71—1

FIG. 1

FIG. 2

FIG. 1 is a perspective view of the multi-stage aerospace craft as it would appear when seen obliquely from above at the front; and

FIG. 2 is a perspective view of the multi-stage aerospace craft as it would appear when seen obliquely below at the rear.

What is claimed is:

The ornamental design for a multi-stage aerospace craft, substantially as shown.
